SIGNAL APPARATUS

Watson E. Bolling, Bonny Blue, Va.

Application June 7, 1937, Serial No. 146,928

1 Claim. (Cl. 200—55)

This invention relates to signal apparatus and has for an object to provide apparatus for controlling and indicating the movement of safety doors employed in mines and other places.

5 A further object of the invention is to provide visible means indicative of a clear and also of an obstructed passage, a switch for the independent operation of said means and including an operating arm, which when in position to 10 cause the switch to operate the clear passage indicating means, serves as a door holder, and when in position to operate the obstructed passage indicating means, serves as a door release.

With the above and other objects in view the 15 invention consists of certain novel details of construction and combinations of parts hereinafter fully described and claimed, it being understood that various modifications may be resorted to within the scope of the appended claims without departing from the spirit or sacrificing any of the 20 advantages of the invention.

In the accompanying drawing forming part of this specification,

Figure 1 is a longitudinal sectional view of a 25 mine passage showing the track and showing a safety door held in unobstructing position with relation to the track by the operating arm of a switch which closes a circuit to a distinctive colored lamp when in door holding position.

30 Figure 2 is a cross sectional view taken on the line 3—3 of Figure 1 looking in the direction of the arrowheads.

Figure 3 is a longitudinal sectional view through the door and switch with a portion of 35 the track shown in plan.

Figure 4 is a diagrammatic view showing the electrical connections of the signal lamps and the switch.

Referring now to the drawing in which like 40 characters of reference designate similar parts in the various views, 10 designates a track, 11 upright timbers, 12 cross sills and 13 longitudinal timbers of a mine passage 14 through which conveying cars are moved in the conventional 45 manner.

For denoting an obstructed passage a safety door 15 is hinged as shown at 16 to one of the uprights 11 and in obstructed passage indicating position, extends transversely across the track. 50 In clear passage indicating position the door is held back from the side of the track as shown in Figure 3 by means of a combined latch and switch operating arm 17 formed of insulating material.

55 The switch operating arm is pivoted to swing

to a horizontal and to a vertical circuit closing position on a pivot pin 18, secured to an upright 11. A conductor bar 19 is fixed to the rear face of the arm, as best shown in Figure 3, and is sufficient in length to bridge an annular series of 5 switch contacts as shown in Figure 1. A pair of these contacts 20, are arranged to be bridged by the bar when the arm is rocked to the horizontal door holding position, and the other pair 21 of these contacts are arranged to be bridged by the 10 bar when the arm is in vertical door releasing position.

The contacts are mounted upon a panel 22 of insulating material which is secured to the upright 11, as best shown in Figure 3.

15 A pair of signal lamps 23 and 24, best shown in Figure 2, are secured to the cross sill 12, and these lamps are of distinctive colors, one for example being red to form visual means indicative of an obstructed passage when energized and the 20 other, for example, being clear to provide visual means indicative of a clear passage.

In wiring the device the contacts 20 are electrically connected to the bright light 23 and to the current supply wire 25 by conductors 26, 27, 25 28 and 29, as shown in Figure 4. A ground contact 30 is disposed on the insulating panel 22 at the center of the bar 19 so that when the arm is in horizontal position to hold the door in unobstructing position the bright light will be energized.

30 The contacts 21 are connected to the current supply wire by conductor wires 31, 32 and the before mentioned wire 26, as also best shown in Figure 4. When the operating arm 17 is in vertical position, that is, in door releasing position, the contacts 21 will be bridged by the bar 19 and the red signal lamp 24 will be energized through closing of the circuit just traced and will form visual means indicative of an obstructed passage. 40

45 From the above description it is thought that the construction and operation of the invention will be fully understood without further explanation.

What is claimed is.

In signal apparatus for mines and other passages, a base plate of insulating material adapted to be secured to an upright timber of the mine or other passage, a switch arm formed of insulating material pivotally connected centrally of its ends to said base plate and projecting at both ends beyond the base plate to form handles for turning the arm, said switch arm being adapted to project beyond the edge of said base plate and form a door latch when swung to a horizontal 50 55

position, a conductor bar on the rear face of the switch arm, said switch arm being adapted to be swung to a vertical circuit closing position and to a horizontal circuit closing position on said base plate, a pair of stationary switch contacts on said base plate adapted to be bridged by said conductor bar when the switch arm is swung to

the vertical circuit closing position, and a pair of switch contacts on said base plate adapted to be bridged by said conductor bar when said switch arm is swung to the horizontal circuit closing position.

WATSON E. BOLLING.
